COMBINED BILGE AND TANK WASHER AND JET PUMP

Charles A. Winslow, Oakland, Calif.

Application December 11, 1944, Serial No. 567,754

2 Claims. (Cl. 103—262)

1

This invention relates to an improvement in a combined bilge and tank washer and jet pump.

In the washing and bailing out of receptacles and particularly in the washing and bailing out of the bilge from boats it is important that a small compact structure be provided which will operate either from a water service line, as when a boat is in dock, or from the water pump forming a part of the power plant of the boat. This structure must be capable of supplying an ample amount of water for the washing operation and at the same time provide a jet pump assembly capable of discharging a maximum amount of fluid which may have accumulated in the bilge or which may be deposited in the bilge as a result of the washing operation.

The present simple and inexpensive device is capable of producing maximum jet pumping action and at the same time and without interference with the pumping operation is capable of discharging a regulated supply of water for a washing operation.

More specifically, the present invention comprehends the use of a unit embodying two separate elements which when assembled provides the ejector pump structure and the water discharge for washing.

One of the primary objects of this invention is to provide a device of the type described in which the two units are so constructed that their manufacture is possible without the use of special machinery or equipment, thus reducing the cost and providing for replacements which can be utilized without special skill or equipment.

Reference will be had to the accompanying drawing forming a part of this specification and wherein like characters of reference designate corresponding parts throughout the several views, in which:

Fig. 1 is a transverse section through the body of a boat showing the present apparatus arranged for use;

Fig. 2 is a longitudinal vertical section of the assembled structure forming the essential parts of the invention, and

Fig. 3 is a section illustrating the nozzle control at the end of the wash pipe.

In illustrating this invention I have shown a boat body A having the usual spaced floor or decking B. The entire main structural unit of the present invention is illustrated by reference character C and to this unit is the connection D forming the fluid pressure line, the connection E representing the suction line for removing the accumulated fluid e, the discharge line F and the 55

hose line G, the latter being the hose for supplying the washing water discharged through the adjustable nozzle H.

Referring now to Fig. 2, it will be seen that the main unit embodies two elements, the first being somewhat in the form of a nipple as indicated by reference character I and having the threaded opening 2 and the lateral hose connection 3. An extension 4 is axially arranged with respect to the threaded opening 2, this extension being formed internally with the tapered jet opening 5 having the reduced tapered extremity to form the fluid ejector when cooperating with the second part of the assembly. The nipple I is formed with the reduced threaded portion 5' and the shoulder 6 by means of which the internally threaded pipe section 7 is connected therewith. The internally threaded opening 2 is provided to receive the coupling member 8 of the hose connection 9, by means of which the fluid pressure supply line D is connected. It will be noted that the coupling member 9 is provided with lateral ears 10 to facilitate the making and breaking of the joint between these parts. The hose connection 3 receives the water discharge hose G and this hose can be further secured by means of the clamp 11, as shown in Fig. 1. The pipe element 7 is reduced to provide the restriction 12 immediately forward of the jet nozzle 13 whereby the discharge of the nozzle creates suction in the pump line E. This line E is illustrated as a hose section and is secured in place by the hose clamp 14 shown in Fig. 1. The end of the suction line or hose section E carries the strainer element 15 in the usual manner, this strainer element preventing the closing of the hose by spacing the extremity of the same from the bottom of the tank or hull and further straining the discharging bilge water to prevent stoppage particularly at the restricted neck 12 of the structure. The outer end of the pipe 7 is provided with a hose connection 16 for receiving the discharge hose F and if desired this latter may be clamped in place by a hose clamp such as shown at 11 or 14.

The accumulating chamber 17 is shown as concentric with the jet opening 5 and the threaded orifice 2. This accumulative chamber is of such capacity as to provide a flow both through the jet 5 and through the hose connection 3 which latter is connected with the washing hose G.

It will be apparent from an examination of the structure heretofore described that all of the parts are generally of conventional commercial design to facilitate manufacture, that the parts can be readily separated and replaced for clean-

ing or repair, and that by virtue of the structure and arrangement of parts the size of the assembly is such as to permit convenient storage.

It will be noted that the size of the jet is such that the entire flow from the water pressure line D will not be necessary to insure efficient operation of the bilge suction line E. Rather the size of the jet 6 is such as to build up a back pressure so that fluid is available for discharge through the washing line G. The end of the washing line G is controlled or regulated by the valve H shown more clearly in Figure 3, and this valve can be used to control not only the supply of washing water but also the amount of suction available at the nozzle 13. It is important to note that the flow through the bilge suction line can be made directly proportionate to the discharge through the pipe G by manipulation of the valve H at the end of this line. This is important in maintaining a constant operation when desired and it is also important in that it permits an increase or decrease of the overboard discharge as may be required in numerous variable conditions.

It will be further obvious to one skilled in the art that the apparatus is capable of forming a permanent discharge mechanism of any capacity and that this discharge may be so regulated as to compensate for any flow permitted through the line G whereby a constant pumping operation is available.

I claim:

1. A combined jet pump and washing apparatus including a jet element, said jet element having a tapered outwardly threaded jet at one end and an enlarged intake opening axially formed at the other end, an accumulator chamber formed between said jet and said inlet, said

chamber being formed with a lateral outlet connection, a flexible conduit connected to the lateral outlet connection, said conduit having a valved nozzle at its free end for manual control of the discharge of fluid from the accumulator chamber for proportioning the discharge through said nozzle and jet, and an angle pipe member, said angle pipe member having an internally threaded opening axially formed with respect to one of its arms for threaded engagement with the threaded jet, and including a restricted wall portion immediately forward of said jet.

2. A combined jet pump and washing apparatus including a jet element having a central tubular body portion defining the outer wall of an accumulator chamber, an outwardly tapered jet extending axially from one end of said tubular body and communicating therewith, said jet having an outer threaded portion and an inwardly projecting annular shoulder defining one end wall of said chamber, said chamber being formed with an internally threaded portion, an inlet connection adapted for threaded engagement with said internally threaded portion and having its end wall defining the other end of said chamber, a lateral outlet connection projecting from said chamber, a flexible conduit including a manually regulated valve connected with said outlet, an angle pipe member having an internally threaded opening axially formed with respect to one of its arms for threaded engagement with said externally threaded jet, said arm having its passageway reduced medially to cooperate with said jet, and the other arm of said angle being adapted for connection with a suction intake connection.

CHARLES A. WINSLOW.
